(57) CLAIM

The ornamental design for an herb keeper, as shown and described.

DESCRIPTION

FIG. 1 is a perspective view of an herb keeper showing my new design.

FIG. 2 is a front elevational view thereof. The rear elevational view is identical to FIG. 2.

FIG. 3 is a side elevational view thereof. The opposing side elevational view is identical to FIG. 3.

FIG. 4 is a top plan view thereof; and,

FIG. 5 is a bottom plan view thereof.

The broken lines in the figures are for illustrative purposes only and form no part of the claimed design.
